(57) **CLAIM**

The ornamental design for a low-profile LED headlight as shown and described.

DESCRIPTION

FIG. 1 is an isometric view of a low-profile LED headlight, showing my new design.

FIG. 2 is a left-side view of the low-profile LED headlight shown in FIG. 1.

FIG. 3 is a right-side view of the low-profile LED headlight shown in FIG. 1.

FIG. 4 is a front view of the low-profile LED headlight shown in FIG. 1.

FIG. 5 is a rear view of the low-profile LED headlight shown in FIG. 1.

FIG. 6 is a top view of the low-profile LED headlight shown in FIG. 1; and,

FIG. 7 is a bottom view of the low-profile LED headlight shown in FIG. 1.

The broken lines are shown for the purpose of illustrating portions of the article that form no part of the claim.

1 Claim, 7 Drawing Sheets
